FREDERIC D. COURTENAY, OF EAST ORANGE, NEW JERSEY, ASSIGNOR TO EMBOSOGRAF CORPORATION OF AMERICA, OF NEW YORK, N. Y., A CORPORATION OF NEW YORK

EASEL

Application filed February 14, 1930. Serial No. 428,380.

This invention relates more particularly to easels of the type used in show windows and upon counters to display advertising cards or the like. An important object of the invention is to provide an improved easel which is designed to render it expansible for accommodating cards or sheets of different size.

Other objects of the invention will appear hereinafter.

In the drawings:

Fig. 1 is a front elevation of my improved easel supporting an advertising card, the expansion of the easel being indicated by dot and dash lines;

Fig. 2 a vertical section taken on the line 2—2 of Fig. 1, upon a larger scale, and with the advertising card removed;

Fig. 3 a rear view of the expansible frame of the easel and its support partly broken away; and

Fig. 4 a detail section taken on the line 4—4 of Fig. 1, upon a larger scale.

The easel structure includes a hollow base 1 which, in the present instance, is a hollow casting in the form of a fluted pyramid. The form of the base may be varied, however. At its apex it is formed with a vertical squared socket 2. Mounted upon the

base is the easel proper comprising a card supporting bracket which includes a short standard 3. This standard is square in cross-section and its lower end is fitted in the base socket 2. A screw 4 is inserted upwardly through an aperture in the bottom of the socket and is threaded into the standard to rigidly hold the latter in place. At its upper end the standard is formed with three flat ears 5 which lie in an oblique plane

and form a support for the body 6 of the easel. The easel body comprises two metal plates 7 and 8, flat and substantially rectangular. Interposed between said plates along the upper and lower edges thereof are two straight parallel spacer strips 9 and 10. Spaced below the strip 9, and between the plates are similar parallel spacer strips 11 and 12. The plates are secured to all of said strips by screws 13, and the rear plate

8 bears against the ears 5 and is firmly fas-

tened thereto by screws 14. Thereby the flat body of the easel is supported at the proper inclination.

A show card, indicated at C, is adapted to rest against the inclined front plate 7 of the easel, and a frame bar 15 is mounted upon the plate along the lower edge thereof to support and frame the lower edge of the card. This frame bar is rigidly secured to plate 7 in any suitable manner and is cut away along its upper edge to form a groove 16 for receiving the edge of the card.

For accommodating cards of different size upon the easel the latter is provided with an expanding frame structure. Said structure includes two side frame bars 17 and 18 to extend along the opposite side edges of the card. A flat rack bar 19 is rigidly secured at one end to the frame bar 17 at a medial point of the latter, and a similar rack bar 20 is similarly secured to the bar 18. Each rack bar extends at a right angle from its attached frame bar. Rack bar 19 is slidably fitted within the easel body in the space between the spaced strips 9 and 11, and rack bar 20 is slidably fitted in the space between spacer strips 11 and 12 to mount the rack bars for longitudinal shifting in parallel relation.

A pinion 21 is disposed within the easel body at a central point between the rack bars, and meshes with the teeth of both bars. This pinion is fixed to a short shaft 22 which extends outward through a bearing aperture in the rear plate 8 and has a knurled operating knob 23 fixed to it at the rear of the easel. When the knob is turned the frame bars 17 and 18 will be shifted equally and in unison to expand or contract the easel frame while maintaining its symmetry. Thereby the easel is rendered adjustable to accurately fit cards of different width and hold them properly centered. Along their inner sides the bars 17 and 18 are grooved as at 24 to receive the side edges of a card. To limit the expansion of the easel frame each rack bar is provided with a stop screw 25. These screws travel in a pair of slots 26 formed in the rear plate 8 and outward move-

ment of the bars is limited by contact of said screws with the outer ends of the slots.

The three frame bars 15, 17 and 18 are longitudinally grooved as indicated at 27 5 and are stepped or cut back at the ends as at 28 to produce a desired ornamental effect.

This design also adapts the easel to support a card of greater height than the frame without any appearance of distortion, as the projecting upper end of the card will appear as 10 a harmonious extension of the grooved and cut back frame.

My expandible easel is designed to be used to particularly good advantage in stores, for 15 displaying published advertisements. Such an advertisement, as it appears in a newspaper or the like, may be mounted upon a card or mat and then placed upon the easel and displayed in a show window or upon 20 a counter. Many shoppers, whether they have noticed the advertisement in the newspaper or not, will be attracted to a certain department of the store if an advertised special or even an ordinary advertised item is 25 brought to their attention by the attractive display of the published advertisement. It has heretofore been inconvenient to do this however because of the fact that advertisements vary greatly in size. My expandible 30 easel overcomes this difficulty in an entirely satisfactory manner. It has a wide range of adjustment and may be readily manipulated to receive cards or sheets of different sizes and frame them accurately and attractively. 35 The expandible easel is also well suited for other uses.

While I have shown and described a very 40 satisfactory form of my invention I do not wish to be limited strictly to this disclosure but reserve the right to make such changes as will lie within the scope of the claims.

What I claim is:

1. An easel structure for supporting a display sheet comprising a base; a standard supported by said base; an easel body supported by said standard; a bar carried by the easel body to support the lower edge of the display sheet; a plurality of side bars to extend along the opposite side edges of the sheet, 45 said bars being longitudinally grooved along their opposed sides to receive the edges of the sheet; means carried by the easel body supporting said side bars for lateral shifting toward and from each other to accommodate sheets of different width; and means manually operable at the back of the easel body to shift said side bars toward and from each other equally and in unison, and thereby center cards of different width upon the easel. 50
2. An expandible easel for supporting a display sheet comprising a pair of side bars disposed in the same plane for engaging opposite side edges of the sheet; laterally adjustable supporting means for the side bars; 55 a base; a mounting for said adjustable sup-

porting means supported by the base and disposed to support the bars elevated; a single adjusting element operable from a point back of the position of the supported sheet for oppositely shifting said adjustable supporting means and oppositely moving the side bars inward and outward equally and in unison; and means carried by the base for supporting the sheet independently of the side bars, between the bars and in the same plane with them, to thereby position the sheet for engagement of the side bars with the opposite side edges of the sheet. 70

3. An expandible easel for supporting a display sheet, comprising a pair of side members disposed in the same plane for engaging opposite side edges of the sheet; adjustable supporting means for the side members connecting them for lateral shifting inward and outward equally and in unison; a base; a mounting for said adjustable supporting means supported by the base and disposed to hold the side members elevated; and means carried by the base for supporting the sheet independently of the side members, between 80 said members and in the same plane with them, to thereby position the sheet for engagement of the side bars with the opposite side edges of the sheet. 90

4. An expandible easel for supporting a display sheet comprising a pair of side bars for engaging the opposite side edges of the display sheet; means for supporting the sheet between the side bars; a pair of supporting and adjusting bars for said side bars each connected to one of the side bars, extending laterally inward from a medial point of the latter toward the other side bar and disposed back of the supported sheet, said adjusting bars having rack teeth therealong; an adjusting pinion centrally located between the side bars and engaging the rack teeth of both adjusting bars to shift them in unison in opposite directions when the pinion is rotated; a mounting supporting the pinion for rotation 100 and the adjusting bars for lateral shifting back of the supported sheet; means back of the position of the supported sheet for turning the pinion; a base; and means supporting said mounting upon the base in an elevated 110 position with the side bars supported elevated above the bottom of the base. 115

5. An expandible easel for supporting a display sheet comprising a pair of side bars for engaging the opposite side edges of the display sheet; a pair of supporting and adjusting bars for said side bars each connected at one end to one of the side bars and extending inward from a medial point of the latter toward the other side bar, said adjusting bars having rack teeth therealong; an adjusting pinion centrally located between the side bars and engaging the rack teeth of both adjusting bars to shift them in unison in opposite directions when the pinion is rotated; an 120

easel body supporting the pinion for rotation and the adjusting bars for lateral sliding movement back of the position of the supported sheet; means back of the easel body for turning the pinion; and means supporting the easel body.

6. An expandible easel for supporting a display sheet comprising a pair of side bars for engaging the opposite side edges of the display sheet; means for supporting the sheet between the side bars; a pair of supporting and adjusting bars for said side bars each connected to one of the side bars and extending laterally inward from a medial point of the latter and toward the other side bar; a mounting including guides located midway between the side bars and supporting the adjusting bars for lateral shifting back of the supported sheet; means to oppositely shift said adjusting bars inward and outward equally in unison; a base; and means supporting said mounting upon the base in an elevated position with the side bars supported elevated above the bottom of the base and inclined to direct the display sheet upward and forward.

7. An expandible easel for supporting a display sheet comprising a pair of side bars for engaging opposite side edges of the sheet; means for supporting the sheet between the side bars; adjustable supporting means for the side bars connecting them for lateral shifting inward and outward equally and in unison; a base; and a mounting for said adjustable supporting means supported by the base and disposed to hold the side bars elevated above the bottom of the base.

8. An expandible easel for supporting a display sheet, comprising a pair of sheet-retaining side members disposed in the same plane for engaging opposite side edges of the sheet; means supporting said members for lateral shifting inward and outward; a base; a mounting for said supporting means supported by the base and disposed to hold the side members elevated; and means carried by the base for supporting the sheet elevated independently of the side members in a position between said members and in the same plane with them, to thereby position the sheet for engagement of the side members with the opposite side edges of the sheet.

In testimony whereof I hereunto affix my signature.

55 FREDERIC D. COURTENAY.
